UNITED STATES PATENT OFFICE.

ORNAN S. COOK, OF FITCHBURG, MASSACHUSETTS, ASSIGNOR TO GALE BOX MANUFACTURING COMPANY, OF WEST FITCHBURG, MASSACHUSETTS, A CORPORATION OF MASSACHUSETTS.

SHOOK HOLDER.

1,411,413.

Specification of Letters Patent. Patented Apr. 4, 1922.

Application filed June 27, 1921. Serial No. 480,920.

To all whom it may concern:

Be it known that I, ORNAN S. COOK, a citizen of the United States, residing at Fitchburg, in the county of Worcester and 5 State of Massachusetts, have invented a new and useful Shook Holder, of which the following is a specification.

This invention relates to a device for holding matched boards in position for forcing them together to produce box sides and ends 10 for use in the manufacture of boxes. Although the invention is capable of use for matching lumber and for other purposes than making boxes, this is the principal use 15 for which it is intended.

The principal objects of the invention are to provide a simple and convenient support for the above mentioned purpose which will accurately hold the boards in position and 20 prevent their buckling while they are being matched; to provide simple and convenient means for forcing the clamping devices into position to prevent this buckling action; and to improve and simplify the various features 25 of the device.

Reference is to be had to the accompanying drawings in which—

Fig. 1 is a plan of a shook holder constructed in accordance with this invention; 30 Fig. 2 is a front elevation;

Fig. 3 is an end elevation; and

Fig. 4 is a sectional view on the line 4—4 of Fig. 3 on enlarged scale.

The device is designed to support a plurality of boards 10 which are tongued and grooved at their edges. For this purpose it involves an inclined frame consisting of two legs 12 at the opposite ends of the holder and a plurality of supports 13 located between them and having their front surfaces parallel with them. This whole structure forms an inclined supporting frame for the boards. These parts 12 and 13 are held together by bottom and top cross pieces 14. 40

The legs 12 are adapted to rest on the floor and the structure is supported in inclined position by rear legs 16 also inclined and fixed to the upper ends of the legs 12 and held together by a horizontal cross piece 17 at the bottom.

The two legs 12 are provided with a supporting plate 20 located near the bottom for receiving the bottoms of the boards 10. This is shown in the form of an angle bar, the up-

per surface of which is slightly inclined. 55 The cross pieces 14 and 17 also can be in the form of angle bars conveniently.

Along the side of one of the legs 12 at the right is a clamping bar 21. This is connected with the leg by a pair of links 22 60 which are capable of swinging on horizontal axes to bring this bar down into clamping position. This bar 21 is preferably an angle iron or otherwise made to have an L-shaped cross section. It is connected by a link 23 65 with a link 24 which also is connected by a similar link 23 with the leg 16. Both links 23 are pivoted at both ends and can move from the dotted line position shown in Fig. 3 to the full line position. Pivoted mounted on a rod 25 which extends across between the legs 16 is a lever 26 having a treadle 27 on its end projecting forward of the front legs 12. 70

For the purpose of guiding the clamping 75 bar 21 I have shown a metal guide 30 fixed to the leg 12 on which this bar is movable.

In the use of the device the boards are placed with their edges horizontal and resting on the support formed of the members 80 12 and 13. The bottom one rests on the plate 20 at its lower edge, and the others extend across horizontally as indicated. The ends of these boards are of course brought into alignment and into a position in which 85 the inwardly extending flange on the bar 21 projects over them. When the parts are in this position the operator steps on the treadle 27 which brings down the clamping bar 21 so that its edge holds the edges of the boards 90 and prevents buckling. Then the boards are matched by forcing them together in the usual way by pounding on a strip of wood applied to the upper edge of the series of boards or shook or by screw pressure if desired. 95

It will be seen that the device simply holds the ends of the boards and keeps them from buckling and getting out of alignment while they are being forced together in the usual 100 way and constitutes a convenient support for them during this operation.

Although I have illustrated and described only a single form of the invention I am aware of the fact that modifications can be 105 made therein by any person skilled in the art without departing from the scope of the invention as expressed in the claims. There-

fore I do not wish to be limited to all the details of construction herein shown and described, but what I do claim is:—

1. In a shook holder, the combination of a support for holding a series of matched boards in inclined position, with means carried by said support and movable on it toward and from its shook supporting surface for clamping one end of the shook in a flat condition and preventing their buckling while they are being assembled.

2. In a shook holder, the combination of a frame comprising an inclined support for the boards of the shook, a movably mounted clamp of L-shaped cross section having a flange extending over the ends of all the boards when so supported and a flange for guiding it at the edge of the support, and means for moving said flange into a position to bear upon the flat surface of said boards and hold them in position.

3. In a shook holder, the combination of a frame comprising front legs and rear legs located at converging angles, the front legs constituting an inclined support for the boards of the shook, a movably mounted clamp having a flange extending over the ends of the shook when so supported and movable toward and from into a position to bear upon the flat surface of said shook and

hold it in position, means for operating the clamp comprising a pair of links, each pivoted to one of said legs and pivoted together, and means for drawing the links down to force the clamp inwardly.

35

4. In a shook holder, the combination of a support for the shook, a clamp mounted along the edge of said support and having a flange adapted to engage the front side of said shook, a link connected with said clamp, a guide for guiding the clamp to move in a plane at right angles to the front surface of the shook, a treadle, and links connected to said treadle for drawing down the clamp when the treadle is depressed.

45

5. In a shook holder, the combination of a frame constituting an inclined support for the boards of the shook, a movably mounted clamp having a flange extending over the end of the shook when so supported and movable toward and from and into a position to bear upon the flat surface of said shook and hold it in position, means for operating the clamp comprising a pair of links pivoted together, and means for drawing the links down to force the clamp inwardly.

In testimony whereof I have hereunto affixed my signature.

ORNAN S. COOK.
